The ornamental design for an ankle joint brace, as shown and described.

DESCRIPTION

FIG. 1 is a front elevational view of an ankle joint brace showing my new design;

FIG. 2 is a right side elevational view thereof;

FIG. 3 is a rear elevational view thereof;

FIG. 4 is a left side elevational view thereof;

FIG. 5 is a top perspective view thereof;

FIG. 6 is a bottom perspective view thereof; and,

FIG. 7 and 8 are side elevational views thereof, the broken line showing is for illustrative purposes only and form no part of the claimed design.
